COMPENSATOR SHEAVE

Harold V. McCormick, Wilmette, Ill., assignor to
Westinghouse Electric Elevator Company, Chi-
cago, Ill., a corporation of Illinois

Application October 29, 1932, Serial No. 640,179

6 Claims. (Cl. 187—22)

My invention relates to idler sheaves and more particularly it pertains to a compensator sheave for tensioning and restraining the compensating cables of elevator systems.

5 In modern elevator systems it is customary to provide compensating cables connected between the car and the counterweight for preventing the unbalancing of the system, as the hoist cables pass over the hoist sheave from the car side to the counterweight side, and vice versa. A weighted idler sheave is usually suspended in the loop of the compensating cables to restrain and guide the cables, and to maintain a predetermined tension thereon.

10 Difficulties have been encountered with the car or the counterweight continuing to rise and developing slack cables, when the descent of the other body is suddenly checked, and thereafter falling back and snapping the cables with possible injury to the equipment and passengers.

15 Additional trouble has also been caused by the weighted compensator sheave flying up from the bottom of the hatchway and then falling back and snapping the cables.

20 Previous attempts to avoid these difficulties by fastening the compensator sheave down to the bottom of the hatchway have not been successful since the total length of the cables in the system does not remain constant, but varies in accordance with changing conditions of wear, loading and temperature. Hence, when the cables were locked down in such a manner as to make a rigid system, abnormal detrimental stresses were set up.

25 It is accordingly an object of my invention to provide a normally free moving elevator compensating cable sheave which will resist upward movement in excess of a predetermined rate.

Another object of my invention is to provide 30 an elevator compensator sheave which will prevent the formation of slack cables by either the car or the counterweight continuing to ascend after the other body is suddenly retarded and which permits the cables to move freely under 35 normal conditions.

A further object of my invention is to provide 40 a normally free moving device for guiding and tensioning the compensating cables of an elevator system which will resist sudden abnormal movements.

45 It is also an object of my invention to provide 45 a lock down compensator sheave of simple rugged design which will move smoothly between its guide rails to permit unlimited normal expansion or contraction of the cables.

The invention itself, however, both as to its organization and its method of operation, together with additional objects and advantages thereof, will best be understood from the following description of a specific embodiment, when read in conjunction with the accompanying drawing, in which:

Figure 1 is a side elevational view of my compensator in operative engaging relation with an associated guide rail; and

Fig. 2 is a section view thereof taken on line II—II.

Referring more specifically to the drawing, the device comprises a cable receiving sheave 1 which hangs in the loop of the compensating 70 cables 2 near the bottom 3 of the elevator hatchway. The hub of the sheave 1 is provided with a bearing 4 through which a shaft 6 extends. The ends of the shaft 6 extend into orifices provided in guide blocks 8 where they are secured by suitable set screws 9. A passageway 10 may carry grease through the shaft to bearing 4.

Each guide block 8 is provided with laterally projecting guide shoes 12 which engage vertically disposed guide rails 13 secured on the bottom 3 80 of the hatchway in any suitable manner. The sheave 1 hangs on the compensating cables 2 and rotates freely on the shaft 6 which is held from rotation by the guide blocks 8.

The upper end of each guide block 8 is provided 85 with a depressed socket 15 which receives the lower end of a long heavy compression spring 16 and a short smaller spring 17 in concentrically disposed relation. Resting on the upper ends of the heavy springs 16 is a weight frame 18 comprising a massive casting, or fabricated structure, 90 having an open portion 19 in each side wall to receive the guide blocks and springs. The upper edge of each opening 19 is provided with a socket 21 which opens downwardly to receive the upper 95 ends of the springs. The heavy springs 16 have sufficient resilience to support the weight frame 18 a predetermined distance from the guide blocks 8, and in normal operation when the sheave 1 is raised or lowered gradually by contraction or expansion of the compensating cables, 100 this relation is not disturbed. Additional weights 22 may be bolted to the weight frame 18 as desired.

In order to guide the movements of the weight 105 frame, it is provided on each side with suitable laterally projecting pairs of guide shoes 23 adjacent its lower and upper edges for cooperative engagement with the same vertical guide rails 13 which also serve to guide the movements of the 110

guide blocks 8. One of each of the lower pairs of guide shoes 23 is provided with an inner surface 25 which is inclined at an angle to the guide rail 13 in addition to a vertical surface 26 which is disposed adjacent the guide rail for cooperative engagement therewith. A wedge 31 is provided for slidable engagement between the inclined surface 25 and the guide rail 13 to apply a braking force resisting upward movement when 10 predetermined conditions occur.

The actuation of the wedge 31 is controlled by a lever 32 to one end of which it is pivotally secured. The lever 32 is mounted on the weight frame 18 on a stationary pivot 33. The outer end 15 of the lever 32 is pivotally secured to a link rod 34 which extends through a bracket 35 projecting laterally from the guide block 8. A resilient means such as a compression spring 36 is provided in concentrically disposed relation on the 20 upper portion of the link rod above the bracket. The upper end of the rod, which is threaded, receives a nut 37 and a washer 38 to hold the spring 36 in engaging relation on the rod and the bracket.

25 In normal operation, variations in the length of the cables are caused by varying temperature conditions, by varying stresses set up by changing load conditions, and by the operation of the system to accelerate or retard the load. During 30 such conditions my compensator tensions the compensating cables at all times without jerking or wearing the guide rails or the cables, since it is free to slide up and down on the rails.

If some abnormal condition occurs which 35 causes the compensator sheave to be jerked up suddenly, the weight frame will lag because of its inertia, the guide blocks 8 will compress the springs 16 and move upward relative to the weight frame 18 thereby pulling up the link rod 34 and 40 rotating the lever 32 to thrust the wedge 31 between the inclined surface 25 and the guide rail 13. The wedge binds between the rail and the inclined surface of the guide shoe thereby applying a braking force which resists upward movement of the weight frame 18. Any movement of 45 the frame upward will cause the wedge to bind still more rigidly against the guide rail.

The spring 36 on the link rod 34 protects the wedge actuating members from breakage by continued upward movement of the guide blocks after the wedge has become rigidly engaged. The upward movement of the cable sheave and the guide blocks is limited by the compression of the heavy springs 16 and the smaller springs 17 55 which are also compressed against the weight frame.

Since the sudden upward movement of the cable sheave is limited, the danger is avoided of either the elevator car or the counterweight 60 rising and developing slack cables and then falling back and snapping the cables when the other body is retarded suddenly.

It will be apparent that I have provided an 65 elevator compensator sheave which, under normal operating conditions, is free to gradually rise and fall any distance necessitated by the stretch-

ing of the cables while applying a constant tensioning force thereto, and which does not wear the guide rails and compensating cables by continual gripping and jerking, and which is of simple, rugged construction.

80 Although I have shown and described a certain specific embodiment of my invention, I am fully aware that many modifications thereof are possible. My invention, therefore, is not to be restricted except as necessitated by the prior art 85 and the scope of the appended claims.

I claim as my invention:

1. A device for tensioning and guiding elevator compensating cables comprising a cable receiving sheave, inertia means, mounting means including resilient member for supporting said inertia means on said sheave, guides for restraining the movements of said sheave and said inertia means, a brake for engaging said guides to retard said inertia means, and means responsive to a predetermined relative movement between said inertia means and said sheave for applying said brake.

90 2. A device for tensioning and guiding elevator compensating sheaves comprising a cable receiving sheave, inertia means, mounting means for supporting said inertia means resiliently on said sheave, guides for restraining the movements of said sheave and said inertia means, an inclined plane carried by said inertia means adjacent each 95 guide, wedges, and means responsive to a predetermined relative movement between said inertia means and said sheave for moving said wedges between said guides and inclined planes.

100 3. A compensator for elevators comprising a cable receiving sheave, an inertia device, resilient means connecting the sheave and the inertia device, a brake for controlling the movements of the sheave and means responsive to a predetermined relative movement of the sheave and the 115 inertia device for operating the brake.

110 4. A compensator for elevators comprising a cable receiving sheave, an inertia device, resilient means connecting the sheave and the inertia device, a brake for controlling the movements of the sheave, and means responsive to a predetermined relative movement of the sheave and the inertia device for operating the brake, said brake operating means including a resilient element for 120 protecting the brake from breakage by a continuation of said relative movement.

125 5. A compensator for elevators comprising a cable receiving sheave, an inertia device, means for supporting the inertia device on said sheave, a brake for controlling the movements of the sheave, and means responsive to a predetermined relative movement of the sheave and the inertia device in an upward direction for operating the brake.

130 6. A compensator for elevators comprising a cable receiving sheave, an inertia device, and means responsive to a predetermined relative movement of the sheave and the inertia device for restraining the movements of the sheave.

135 HAROLD V. McCORMICK.
